(57) **CLAIM**

The ornamental design for a medicine container as shown and described.

DESCRIPTION

FIG. 1 is a perspective view of a medicine container showing my design;

FIG. 2 is a second perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines of the drawing show portions of the medicine container that form no part of the claimed design.
